(57) **CLAIM**

The ornamental design for a door closure device, as shown and described.

DESCRIPTION

FIG. 1 is a perspective view of the present invention; FIG. 2 is a front elevational view of the present invention; FIG. 3 is a right side elevational view of the present invention, the left side elevational view being a mirror image thereof; FIG. 4 is a rear elevational view of the present invention; FIG. 5 is a top plan view of the present invention; FIG. 6 is a bottom plan view of the present invention; and, FIG. 7 is another bottom plan view of the present invention which shows the interior of the device. The broken lines represent portions of the structure that form no part of the claim.
